UNITED STATES PATENT OFFICE.

ALFRED CHRISTIAN JONASSEN, OF ANERLEY, LONDON, ENGLAND.

AUTOMATIC REPEATING TOY PISTOL.

Application filed October 3, 1925, Serial No. 60,305, and in Belgium October 27, 1924.

The invention relates to a toy pistol arrangement especially adapted for the projection of small objects, and for example marbles and such that a certain number of these objects may be automatically projected in succession, the mechanical arrangement enabling such projection being simpler in construction and more certain in operation than in the pistols of this kind already proposed. To this effect it consists principally in providing between the barrel and the projectile magazine a channel or passageway at the entrance of which said projectiles are brought successively and in which they are, on the one hand introduced by means of an operating lever, integral with or controlled by the trigger member, and on the other hand retained against backward displacement by means of a member either elastic or operated by a spring, and of which the deformation is such—when the projectile is travelling in the said passage—that the projectile, passing into the barrel, is urged in the direction of the latter and projected by the trigger member on the return movement of the said member to its initial position.

The invention also consists in shaping the operating lever in such a manner that the projectile introduced into the passage is completely sustained and guided by the end of the lever on which it bears, while at the same time the other projectiles of the magazine are retained in the latter pending their projection.

The invention also consists in providing in the casing or shell of the pistol an opening enabling the magazine to be recharged with projectiles without necessity of removal of any part of the pistol.

The invention further consists in certain other special arrangements to which reference will be made in the detailed description of preferred forms of pistols embodying the invention, represented by way of example in the accompanying drawings in which:

Fig. 1 is a longitudinal section of a toy pistol according to the invention, showing the members of the ejecting mechanism in the inactive position.

Fig. 2 is a similar view showing in plain lines the positions occupied by the said members in the firing position and in dotted lines the same members in intermediate positions.

Fig. 3 is a partial longitudinal section of a modified constructive arrangement of the trigger member and its return spring.

Fig. 4 is a section taken on line A—B of Fig. 1.

Fig. 5 shows a preferred arrangement of a modified elastic member effecting the projection.

Fig. 6 is a detailed view, on enlarged scale of the arrangement shown in Fig. 1, showing the means employed for limiting the stroke of the spring carrying the projectiles in the magazine.

Fig. 7 is an alternative form of the arrangement shown in Fig. 1.

Fig. 8 is another alternative form of the same arrangement, the magazine being disposed in the butt.

Fig. 9 is a view similar to that of Fig. 8, an opening being provided in the casing for filling the magazine.

Fig. 10 is a partial section of another alternative construction.

Fig. 11 shows, in plan, the shape to be adopted for the operating lever.

Fig. 12 is a detail.

Fig. 13 is a cross sectional view of an alternative construction of the pistol casing.

The same reference characters designate the same or similar members in the various figures and as represented 1 designates the casing or body of the pistol as a whole, said casing being formed of two symmetrical halves assembled along their upper and lower edges by members 2. Each half of the casing is preferably stamped out of sheet metal of suitable thickness, and formed with a barrel 3 and a magazine 4, the latter being parallel to the barrel in the forms shown in Figs. 1, 2, 3 and 7 and approximately perpendicular to the barrel in the forms shown in Figs. 8, 9 and 10. These parts are given either a semi-circular shape (Fig. 4) or a shape more or less rectangular (Fig. 13), leaving however in each case a certain clearance 5 between the central portions which enables certain parts of the operating mechanism to be located therein and insures the correct trajectory of the projectile by guiding it along the edges 5¹ of the barrel.

In the form represented in cross section in Fig. 4 the barrel 3 has preferably a diameter approximately equal to that of the projectiles whereas the section of the magazine is slightly larger, so that a small shoulder 4¹ may be formed at the rear end of the latter, said shoulder acting as a stop for an approximately hemispherical cap 4² mounted on the end of the spring 6 causing the dis-

placement of the projectiles, or for the end of the spring itself, a few turns of which are brought together so as to form a cap as shown in Figs. 9 and 10.

5 In the construction shown in Fig. 13, since the section of the magazine is rectangular, the cap 4² on the spring 6 is shaped accordingly, the stop 4¹ being formed in this case by four projections in the angles of the 10 magazine.

A channel or passage 7 is formed between the barrel 3 and the magazine 4, the said passage being simply straight, as in the forms shown in Figs. 1, 2, 3, 7 and 10, or 15 with curved front and rear walls, as in Figs. 8 and 9, the cross section being in each case sufficient to allow the passage of the projectiles used.

In the said passage 7 is disposed a member 8 either elastic in itself (Figs. 1, 2, 3, 8 and 9) or controlled by a spring (Figs. 7 and 10), and of such a shape that it stops the passage 7 when in its inactive position but becomes so deformed or displaced, when 25 the projectile is introduced and forced in the passage by the action of a lever 9, as to move in the direction of the barrel at the rear side of the projectile, so as, by expansion, to expel the said projectile from 30 the said barrel.

The projectiles are introduced into and forced up along the passage 7 by means of a lever 9, integral with the trigger 10 (Figs. 1, 2, 3, 7, 8, 9) or operated by the latter 35 (Fig. 10), and preferably formed as forked member (Fig. 11) so as to support the projectile on a relatively large part of its surface and guide it securely. The said lever has a special shape such that, when acting 40 on the trigger 10, a projection 11 will be inserted between the projectile 12 of the magazine 4 which is at the entrance of the passage 7, and the following projectile—or the cap 4² on the spring 6 if the last projectile is concerned—so as to act, by means 45 of the part 13, on the projectile to be expelled and cause it to travel in the passage 7, and by means of its part 14, on the projectiles remaining in the magazine, and prevent any forward movement of the latter 50 (see especially Fig. 2).

The parts 13 and 14 on the lever 9 have circular outlines adapted to the curvature of the projectiles 12. The lever 9 is either 55 formed integral with a trigger 10 (Figs. 1, 2, 3, 7, 8 and 9) pivoted on a fixed pin 15 riveted or attached to the casing of the pistol, or else pivoted at 15¹ on the trigger, as shown in Fig. 10. In each case a spring 16 is provided to return the lever and the trigger back to their inactive positions 60 (Figs. 1, 3, 7, 8, 9 and 10). If desired the operating lever 9 may be provided with an elastic stop which is formed either on the 65 lever itself or on the operating spring.

The operation of the pistol according to the invention may be readily understood. It is as follows:

Assuming that projectiles have been introduced into the magazine 4, the first one 70 will come at the entrance of the passage 7, bearing against the member 8, the other projectiles following in the magazine. If the trigger 10 be operated, the projection 11 on the lever 9 will be inserted between the projectile occupying the entrance to the passage 7 and the following projectile—or the cap 4²—the part 13 of the said lever engaging the formed projectile into the passage 7, while the part 14 retains the other projectiles in the magazine. 75

Under the action of the lever 9, the projectile to be expelled is forced up along the passage 7, bending or pushing back the member 8 until it reaches the outlet of the said passage, that is to say the position shown in full lines in Fig. 2.

At this instant, the projectile is free to move towards the mouth of the barrel and the bending or elastic displacement of the member 8 is a maximum and such that the pressure exerted on the projectile is approximately parallel to the axis of the barrel. The expulsion takes place with a force proportional to the elastic force of the member 8 or to the power of the return spring. 90

After the shooting operation, the member 8 returns to the position closing the passage 7 and on the other hand, if the trigger 10 is released, the lowering of the lever 9 100 will permit the advance of the projectiles of the magazine and the various parts will be ready for shooting again.

In order to enable the easy loading of the magazine 4 without removing the spring 6, an opening 17 is provided in the casing of the pistol, at the rear end of the magazine, towards the inlet of the passage 7. The opening 17 uncovers a portion of the magazine corresponding partially with the positions of the first two projectiles or of the last projectile and the cap, so that a projectile introduced through the said opening will be inserted between two succeeding projectiles or between the last projectile and the pusher 4², or else before the latter. 110

This simple arrangement enables the pistol to be reloaded very easily and rapidly.

In the constructions represented in Figs. 1 and 2, there is provided a cap 18 closing the front end of the magazine and against which bears the end of the spring 6. This cap is shown in perspective in Fig. 12 and is fixed to the pistol casing 1 by means of a bayonet joint indicated at 18¹ and 18². 120

Further, in the said figures, the end of the trigger 10 moves in a guard of U-shaped section, the ends 19 of which are fixed, by means of parts bent at right angles, in the openings 20 cut in the two halves of the 130

casing. However, one side of one of the ends of the guard is not bent but used as a support for attaching the return spring 16 of the lever 9.

5 The member 8 is in this case formed as a flat spring a part of which is held between two stamped ribs 8² formed on the inside of each half casing. This spring 8 is reinforced by a second spring 8³ bearing on the frame 10 as shown in the said figures.

The same general arrangement is maintained in the form shown in Fig. 3, but the trigger 10 is enlarged, so that it is never completely disengaged from the casing 1.

15 It will further be noted that the spring 16 is replaced by an extension 8⁴ on the member 8, the mechanism being thus reduced to a single spring and a trigger member, the upper part of the said spring being shaped, 20 for example, as shown in Fig. 5.

Fig. 6 shows the shape of the cap 4² on the spring 6 as well as the shoulder 4¹ which acts as a stop for the said cap.

In Fig. 7, the member 8 is formed as a 25 lever pivoted at 8⁵, the position of the said pivot being selected so that the upper end of the said lever will act in the same way as the spring in the preceding examples. A return spring 8⁶, of suitable strength, connects the lower end of the lever to a fixed point at the rear of the pistol casing 1.

The general arrangement shown in Figs. 1 and 2 is again found in the form shown in Fig. 8.

35 In this case the member 8 is held at the central part between two ribs 8² formed on the inside of the casing 1.

In this figure the magazine is recharged by removing a cap 22 (also fixed to the base 40 of the casing by means of a bayonet joint) and by removing the spring 6, one end of which may be attached to the said cap.

In Fig. 9 the flat spring is replaced by a wire spring having two parallel branches, 45 hooked at one end into suitable openings 21 in the casing 1, or simply bearing against the latter.

In Figs. 8 and 9, the passage 7 is continued as a downwardly extending pocket 50 forming a magazine within the handle the principle and the operation being the same as previously.

Finally, in Fig. 10, the lever 9 is connected to the trigger 10 by means of the pivot 15¹, and moreover the member 8 is constituted by a lever pivoted to a fixed point and pressed by a spring 8⁶, said lever being provided with a bended end coming against the spring when returning to the inactive 60 position and thus avoiding any shock against the sides of the barrel or of the passage 7.

Claims:

1. An automatic repeating toy pistol, 65 adapted for the projection of small objects

and specially marbles, comprising in combination a barrel, a projectile magazine, a channel between said magazine and barrel, projectiles to be brought successively at the entrance of the channel, means actuated by 70 the trigger to force the projectile into the channel and means to retain such projectile at the entrance of such channel, said latter means adapted to be forced back by the advance of the projectile into the channel and 75 to expel said projectile along the barrel at the outlet of the channel.

2. An automatic toy pistol comprising in combination a barrel and a projectile magazine, a channel between said magazine and barrel, projectiles in the magazine and means 80 to lead successively the projectiles at the entrance of the channel, a trigger, a trigger operated lever, means on the lever to lead a projectile in the channel and simultaneously retain the other projectiles into the magazine, and retaining means into the channel, said means adapted to be forced back upon advance of the projectile in the channel and to expel said projectile along 85 the barrel at the outlet of the channel.

3. In an automatic toy pistol according to claim 2, a trigger operating lever having an angular projection formed thereon and cam shaped surfaces on either side of said 95 projection, one cam shaped surface adapted to lead a projectile into the channel, the other cam shaped surface adapted to simultaneously retain the other projectiles into the magazine and the angular projection 100 adapted to be inserted between the projectile in position at the entrance of the channel and the other projectiles of the magazine upon actuation of the trigger.

4. In an automatic toy pistol according 105 to claim 2, a trigger operated lever formed of two parallel branches, and means to restore said lever in its inactive position.

5. In an automatic toy pistol according 110 to claim 2, retaining means comprising a spring controlled member disposed in and diagonally across the channel, and anchored in the pistol casing.

6. In an automatic repeating toy pistol according to claim 2, wherein the projectile 115 magazine is formed toward its rear end with an opening to permit the introduction of projectiles into the magazine, said opening uncovering a part of the magazine which corresponds in part with the positions of the 120 first two projectiles in the magazine.

7. In an automatic toy pistol as claimed 125 in claim 2, wherein the magazine is formed with an uncovered feed opening, a projection arranged within the magazine adjacent this opening, and a hemispherical cap on the projectile leading means adapted to bear against the said projection.

In testimony whereof I affix my signature.
ALFRED CHRISTIAN JONASSEN.
